Heb.

UNITED STATES PATENT OFFICE.

JENNINGS NELSON, OF CHICAGO, ILLINOIS.

HYDROMETER SYRINGE.

Application filed November 5, 1923. Serial No. 672,756.

To all whom it may concern:

Be it known that I, JENNINGS NELSON, a citizen of the United States of America, residing at Chicago, in the county of Cook and State of Illinois, have invented a certain new and useful Improvement in Hydrometer Syringes, of which the following is a specification.

This invention relates to that type of portable hydrometric instruments, generally known as hydrometer syringes, and used to ascertain the specific gravity of the acid charges of storage batteries, and has for its object;

15 To provide a structural formation and combination of parts in the view portion or transparent barrel of the instrument, by means of which unimpeded movement of the contained hydrometer is attained, and the usual tendency to adhesion or sticking of the hydrometer body to the inner surface of the syringe barrel after a period of actual use is prevented, all as will hereinafter more fully appear.

20 25 In the accompanying drawing:—

Fig. 1, is a side elevation of a hydrometer syringe to which the present improvement is applied.

Fig. 2, is a detail vertical section of the 30 upper portion of the syringe.

Fig. 3, is a horizontal section.

Fig. 4, is a perspective view of the preferred form of the guide member of the improvement.

35 40 Like reference numerals indicate like parts in the different views.

As represented in the drawing, the syringe comprises a central transparent body portion 1 of an elongated cylindrical form, provided at its respective ends with out turned flanges or beads for the secure attachment of the upper elastic operating bulb 2, of rubber or the like, and for a like attachment of the lower flexible inlet-outlet tube or nozzle 3. The described construction is usual

to hydrometer syringes now in general and extended use.

The material part of the present improvement consists in the arrangement in the interior of the syringe barrel 1, of a plurality 50 of longitudinally extending guide bars or rails 4 in contact with the inner surface of the barrel 1, and preferably formed integral with top and bottom rings 5, to attain proper space relation one to the other. The 55 bars or rails 4 and rings 5 are formed of celluloid or like resilient material, with said rings 5 slit or gapped at 6, so that the expansion resiliency in the material will tend to press the device closely against the inner surface of the barrel 1.

In the present improvement the bars or rails 4, act in a very effective manner as guides for the body of the hydrometer in its movement up and down in the syringe 65 barrel 1, without liability to the usual surface adhesion of parts which occurs in the ordinary type of the instrument.

Having thus fully described my invention what I claim and desire to secure by 70 Letters Patent, is:—

1. In a hydrometer syringe, the combination of the central transparent body of the syringe, and a plurality of longitudinal bars integrally connected together by end rings 75 of a flat band form adapted for frictional holding contact with the inner surface of said transparent body.

2. In a hydrometer syringe, the combination of the central transparent body of the 80 syringe, and a plurality of longitudinal bars integrally connected together by resilient end rings having a gapped form adapted to maintain the parts in contact with the inner surface of said transparent 85 body.

Signed at Chicago, Illinois, this 2nd day of November 1923.

JENNINGS NELSON.
